(57) **CLAIM**

The ornamental design for a head garment, as shown and described.

DESCRIPTION

FIG. 1 is a perspective view of a head garment showing our new design, in a used condition on a human figure shown in broken lines;

FIG. 2 is a rear view thereof, without the human figure in broken lines and shown in an unused condition unwrapped; FIG. 3 is top perspective view of FIG. 1, without the human figure in broken lines;

FIG. 4 is a left-side perspective view thereof;

FIG. 5 is a front-side perspective view thereof;

FIG. 6 is a right-side perspective view thereof; and,

FIG. 7 is a rear, bottom-side perspective view thereof.

The solid lines extending along the outer edges of the head garment form the claimed design. Further, the space between solid lines and the dash-dash broken lines form no part of the claimed design.

The broken lines in FIGS. 1-7 do not form a part of the claimed design. The fabric is shown broken away in FIGS. 1-6 to indicate that no particular length is claimed.

1 Claim, 7 Drawing Sheets
